UNITED STATES PATENT OFFICE.

KARL HELLNER, OF FALUN, SWEDEN.

ROTARY BOILER.

1,390,965.

Specification of Letters Patent. Patented Sept. 13, 1921.

Application filed June 3, 1919. Serial No. 301,552.

To all whom it may concern:

Be it known that I, KARL HELLNER, engineer, subject of the King of Sweden, residing at Falun, Sweden, have invented certain new and useful Improvements in Rotary Boilers, (for which I have filed an application in Sweden, May 28, 1918, No. 2061-18,) of which the following is a specification.

10 The present invention relates to heating elements which are arranged outside the boiler, rotated with the boiler, and connected with the inner chamber of the boiler, so that the liquid to be boiled may pass freely 15 through the elements and heated by means of pipes located in the boiler, which pipes are connected with the hollow shaft pins, so that the steam may enter one shaft pin and the condensed steam allowed to pass from 20 the other shaft pin.

A practical embodiment of my invention is represented in the accompanying drawing, in which,

Figure 1 represents an elevation of my improved boiler, a portion of which is broken away to show parts within.

Fig. 2 represents a plan view of the same.

Fig. 3 represents a longitudinal section, on an enlarged scale, of one of the heating 30 elements.

Fig. 4 represents a horizontal section taken in the plane of the line IV—IV of Fig. 3, looking in the direction of the arrows, and

Fig. 5 represents a horizontal section of a modified form of boiler, on the same scale as Figs. 1 and 2.

The boiler, denoted by 1, is preferably of cylindrical form having an upper spherical 40 and a lower conical part, and provided with hollow shaft pins 2, 3.

Heating elements 4 are arranged, in the present instance, in sets of three upon opposite sides of the boiler, parallel to its longitudinal axis and at right angles to the axis of rotation. These elements each consist of a flanged pipe of suitable length and diameter and provided with short angle branches near its ends, which branches have flanges 50 arranged to be attached to pipe studs 5 on the boiler. Each element 4 is closed at its ends by end pieces 7, 8. A steam pipe 9 is arranged in the hollow shaft pin 2 and connects with a pipe 10 having a T connection 55 11. A pipe 12 leads from one branch of

the T connection 11 and is connected to one set of heating elements by branches 14, each of which is secured to an end piece 7 of the heating elements. A pipe 13 leads from the other branch of the T connection 11 and is 60 connected to the other set of heating elements by branches 15, each of which is secured to an end piece 7 of its set of heating elements.

It should be noted that the upper end of 65 the heating elements 4 at the right of the shell 1 (Fig. 1) corresponds to the lower end of the left hand elements. That is, steam enters at the upper end of the left hand elements 4 but at the lower end of the 70 right hand elements.

In Figs. 1 to 4 inclusive, each heating element is provided with a series of pipes 6, one end of each pipe being fixed in a tube sheet 23 which is secured between the heating 75 element 4 and the end piece 7. The other end of each pipe is secured to a cup shaped member 24 which forms together with a tightening ring 25 and another cup shaped member 26, a receptacle 28 for the reception 80 of the condensed steam passing from the pipe 6.

The members 24 and 26 are drawn together on the tightening ring 25 by means of screw clamps 27. The condensed steam 85 is discharged from the receptacle 28 through a pipe 29 extending from the bottom 26 and passing through a packing box 30 in the end piece 8 of the heating element. The pipe 29 is connected with branches 16 extending outwardly from a pipe 17, which is coupled to the hollow shaft pin 3 by means of pipes 18, a T connection 19 and a pipe 20, which enters the hollow shaft pin 3 and is connected to the outlet pipe 21 of the 90 shaft pin 3.

In the form shown in Fig. 5, a pipe 9* passes through a hollow shaft pin 2* to the inside of the boiler 1 and is connected to a pipe 10*, which passes outwardly through the boiler to a T connection 11*. From the T connection 11*, the arrangement of the pipes for the admission of steam to the heating element 4 is similar to that described in Figs. 1 to 4 inclusive. The hollow shaft 105 pin 3* is provided with a steam outlet pipe 21*, which passes to the inside of the boiler and is connected with a pipe 20*. This pipe 20* passes outwardly through the boiler to a T connection 19*. The arrangement of 110

pipes for the exhaust steam passing through the T connection 19* is similar to that described in Figs. 1 to 4 inclusive.

In Fig. 5, I have also shown each heating element 4 as having a single pipe 6* through which the steam passes to heat the fluid in the element. In both forms shown, I provide perforated screens 22 so located in the boiler as to cover and protect the openings 10 to the pipe studs 5, thereby preventing solid particles from entering the heating elements.

It will be seen that by the construction and arrangement by which the pipes 6 and 15 6* are mounted in the heating elements, a free expansion and contraction of the pipes is obtained. Furthermore, the pipes may be readily removed from the heating elements, for cleaning and repairing and replaced with a minimum of labor and delay. 20 It is also obvious that a complete heating element may be removed or exchanged, equally as well, as the pipe supporting devices.

25 While I have shown and described a boiler arranged with its longitudinal axis at right angles to the axis of rotation, it will also be understood that the arrangement may be applied to a boiler, the axis of which coincides 30 with the axis of rotation. In order to obtain a compact structure and occupy the smallest possible space in its rotation, the heating elements may be curved along circular lines corresponding to the walls of the boiler.

35 During certain periods in the manufacture of cellulose or similar material by this device, it may be found necessary to stop the rotation of the boiler and hold the same in a fixed position. In this position the heating 40 elements are vertically disposed with respect to the longitudinal axis of the boiler and filled with fluid so that the steam may be passed through the elements and discharged at the lower end, either through the shaft 45 pin or a separate conduit removably coupled to the apparatus in any well known manner.

As the fluid, surrounding the pipes in the heating elements, is heated, it moves upwardly and enters the boiler through the 50 uppermost pipe studs 5, while the less heated fluid will enter the elements through the lowermost pipe studs, thereby producing a uniform circulation of the fluid through the heating elements and boiler. The volume of 55 fluid contained in the heating elements is comparatively small in relation to the heating surface of the pipes in the elements with which the liquid comes in contact, the result of which is a very active circulation of the 60 fluid and an efficient heating obtained.

After the fluid has been boiled the desired time in this fixed position, the boiler may be rotated and the steam regulated so as to produce a uniform condition of the boiled material, after which the rotation of the boiler

may be stopped and prepared for the next heating process.

By reason of the boiler being rotated in the direction of the arrow shown in Fig. 1, and the heating elements moved in a longitudinal direction in planes perpendicular to the boiler shaft, the fluid will flow freely and undisturbed along the heating surfaces of the elements and an effective, uniform and thorough heating of the fluid will result. 70 As the heating surfaces in their movement are alternately brought into contact with the fluid, it has been found that no precipitations cover the pipes forming the heating surfaces, which therefore do not require 80 much attention. The condensed steam is also discharged with the passage of steam through the pipes 6 in the opposite direction to the rotation of the boiler so that the conduction of heat may not be impaired. 85

Thus it will be seen that by the construction and arrangement of the parts a maximum production may be obtained with the minimum of operation due to the free passage of steam and the rotation of the parts. 90

What I claim as new and desire to secure by Letters Patent of the United States is:

1. A rotary boiler, characterized thereby, that outside the boiler there are arranged heating elements, provided with inner pipes 95 for the passage of steam, said elements rotating with the boiler and permitting the boiling fluid to pass freely along the heated surfaces during the rotation, in order by this rotation to obtain a favorable fluid circulation through the heating elements along the heated surfaces, thereby effecting a uniform and effective heating of the goods. 100

2. A rotary boiler according to claim 1, characterized thereby, that the heating elements are arranged in such a way, that steam supplied to their pipes passes through the pipes in opposite direction to the movement of the elements in order that the condensed steam may easily be discharged by 105 means of the rotation, thus effecting a free passage of the steam and the conduction of heat depending thereon.

3. A rotary boiler according to claim 1, characterized thereby, that each heating element is of cylindrical shape and near the ends provided with sidewise projecting, short branch pipes of suitable diameter with flanges, secured to corresponding short pipe studs on the boiler, in order to obtain the 115 shortest possible and free passage for the fluid to the heating elements, enabling the fluid to easily and without disturbance fill up the space around the pipes, and then enter the boiler during the rotation. 120

4. A rotary boiler according to claim 1, characterized thereby, that the inner pipes in the heating element form a bundle of parallel pipes, having the one end secured to a tube sheet at the one end of the heating ele- 130

ment, where the steam enters, forming the one wall of the fluid receptacle, and the other end secured to a cup shaped member, which member together with another one, suitably 5 tightened and united, forms a closed chamber for receiving and discharging the condensed steam, which is discharged through an outlet pipe from said chamber, said pipe extending through a packing box on the end 10 piece of the heating element, in order partly to permit free expansion of the pipes and partly to facilitate the removal of those pipes from the heating element for cleaning, repairment or exchange.

In testimony whereof I affix my signature 15 in presence of two witnesses.

KARL HELLNER.
